UNITED STATES PATENT OFFICE

2,416,712

FIREARM CHAMBER LOADING INDICATOR

William H. Parker, Millville, N. J.

Application November 3, 1944, Serial No. 561,739

1 Claim. (Cl. 42—76)

1

The present invention relates to new and useful improvements in firearms and more particularly to safety means therefor whereby the user of the firearm can easily determine whether or not the same is loaded.

More specifically, the invention embodies the provision of a window opening in the barrel of the firearm adjacent the breech or inner end thereof and through which the user of the firearm may see whether a cartridge or shell is in firing position in the barrel.

A further object is to provide safety means for firearms of this character of simple and practical construction, which is efficient and reliable in use, relatively inexpensive to manufacture and otherwise well adapted for the purposes for which the same is intended.

Other objects and advantages reside in the details of construction as more fully hereinafter described and claimed, reference being had to the accompanying drawings forming part hereof, wherein like numerals refer to like parts throughout, and in which:

Figure 1 is a fragmentary top plan view of a single barrel shot-gun constructed in accordance with the present invention.

Figure 2 is a fragmentary longitudinal sectional view through the rear portion of the barrel, and

Figure 3 is a transverse sectional view taken substantially on a line 3—3 of Figure 2.

Referring now to the drawings in detail, wherein for the purpose of illustration I have disclosed a preferred embodiment of the invention, the numeral 5 designates the barrel of a shot-gun or similar firearm adapted for receiving a cartridge 6.

An opening 7 is formed in the top of the barrel, the opening in the present instance being of rectangular shape with the edges of the opening tapering inwardly as shown in Figures 2 and 3 of the drawings. However, said opening may be of any other desirable form.

Snugly fitted in the opening is a transparent plug 8 of glass or other transparent plastic material, the inner surface of the plug being curved as shown at 9 flush with the bore of the barrel to prevent interference with the insertion of the cartridge 6 therein.

2

The edges of the opening 7 adjacent the outer surface of the barrel are formed with a groove 10 and the adjacent edges of the plug 8 are likewise formed with a groove 11 within which a spring wire snap ring 12 is seated to retain the plug against accidental displacement within the window opening 7.

The cartridge 6 is usually constructed of a brilliant color so that when the same is inserted in the barrel 5 the cartridge will be readily seen through the transparent plug or window 8 and the fact that the gun is loaded will then be immediately apparent to users thereof.

While I have illustrated the invention as used upon a single barrel shot-gun it will be apparent that the same is adapted for use upon double barrel shot-gun or other types of firearms in which cartridges or shells are used.

It is believed that the details of construction, manner of use and advantages of the device will be readily understood from the foregoing without further detailed explanation.

Having thus described the invention, what I claim is:

25 A barrel for firearms of a type including a cartridge chamber adapted for firing a cartridge, said cartridge chamber having an opening in its wall in the region of the cartridge, a transparent plug fitted in said opening, the walls of said opening and the edges of said plug having grooves formed therein and a snap ring seated in said grooves.

WILLIAM H. PARKER.
